ELECTRON DISCHARGE DEVICE

Otto H. Schade, West Caldwell, N. J., assignor
to Radio Corporation of America, a corporation
of Delaware

Application May 30, 1942, Serial No. 445,186

3 Claims. (Cl. 175—363)

This invention relates to a power supply circuit, and more particularly to a circuit for providing plate voltage for sawtooth deflection voltage generators for cathode ray tubes.

In some applications of cathode ray tubes, it is desirable to produce a deflection of constant amplitude at a constant repetition rate, but having a variable velocity of sweep and a correspondingly varying period of dwell between successive deflections. A consideration of the power requirements of a sawtooth sweep generator or sweep amplifier in this type of service shows that a plate supply having high voltage and low current capability is required with a high velocity sweep, and one having relatively low voltage and high current capability is required with a low velocity sweep. For example, assume the deflection repetition time to be fixed at 1000 microseconds. In a magnetic deflection circuit, a constant deflection amplitude requires a constant peak current; assume this to be 200 milliamperes. The average value of a cyclically repeating sawtooth current pulse is one half the peak value multiplied by the ratio of the duration time of the sawtooth to the repetition time. Thus a wave having a peak current of 200 milliamperes requires an average current of 100 milliamperes for a pulse of 1000 microseconds duration, 10 milliamperes for a pulse of 100 microseconds duration and 1 millampere for 10 microseconds duration, with a repetition time of 1000 microseconds.

The saw tooth current develops a voltage drop on the deflection coils given by

$$E = L \frac{I_{\max}}{t} + I_{\max} R$$

where L is the inductance of the coils and R is the resistance. For $L=25$ millihenries and $R=70$ ohms, the corresponding voltages E are listed with the average currents I in the following table as a function of t , the duration time for a repetition time of 1000 microseconds:

t	E	I	E_B	P
1,000	5±14	100	100	10
100	50±14	10	145	1.45
10	500±14	1	595	.595

The last two columns give the required plate supply voltage and power input for a power tube operating at a minimum plate potential of 80 volts. It is evident that in this particular case

a power supply of around 600 volts is necessary in order to deflect the beam across the screen in 10 microseconds, repeating at intervals of 1000 microseconds. The average current required is only 1 millampere. However, an average current of 100 milliamperes is required to deflect the beam in 1000 microseconds, repeating every 1000 microseconds.

A constant voltage power supply capable of meeting the foregoing requirements would deliver 60 watts to the plate of the power tube when the sawtooth duration time is 1000 microseconds, and only 10 watts power is required. The remaining 50 watts would be dissipated in heating the power tube. If, on the other hand, the plate supply voltage is varied inversely as the sawtooth duration time, only one sixth as much power is necessary. There is correspondingly less heating of the power tube, and the power supply can be smaller and consequently lighter and cheaper.

Accordingly it is an object of my invention to provide an improved device for supplying plate voltage for sawtooth wave generators and amplifiers. A further object of the invention is to provide an improved variable voltage power supply suited to the peculiar requirements of a constant amplitude, constant repetition time sawtooth wave generator or amplifier, as described above. Still another object is the provision of an improved power supply unit having automatic regulation such that it supplies a voltage which is a predetermined function of the load. These and other and incidental objects will become apparent to those skilled in the art upon consideration of the following description, with reference to the accompanying drawing, in which Figs. 1a, 1b and 1c are graphs of sawtooth waves; Fig. 2 is a schematic block diagram of the device of the invention; and Figs. 3 and 4 are circuit diagrams of two specific embodiments of the invention.

Referring to Figs. 1a, 1b and 1c, the sawtooth waves A, B and C each have a repetition time of 1000 microseconds, and a peak amplitude of 200 milliamperes. The duration of each pulse of the wave A is 1000 microseconds, of wave B, 100 microseconds, and wave C, 10 microseconds. The average current in each case is the area within the sawtooth divided by the ratio of repetition time to sawtooth time. It is apparent from examination of Fig. 1a that the slope of the sawtooth varies inversely as its duration. The rate of change of current with respect to time is highest when the sawtooth duration is shortest, pro-

ducing the largest inductive drop in the deflecting coils through which it is conducted.

Referring to Fig. 2, two power sources 1 and 3 are connected in series in the plate circuit of the tube 5, which also includes the cathode ray deflection coils L. The source 1 is adapted to provide a low voltage and high currents, for example, 150 volts and 100 milliamperes, with good regulation, and the source 3 is adapted to provide high voltage and low current, such as 450 volts and 1 milliampere, with relatively poor regulation. A diode 7 is connected across the source 3 to short circuit it when large currents are required to prevent an output voltage drop below that of the low voltage supply 1.

Referring to Fig. 3, a full wave low voltage rectifier 9, capable of supplying, for example, 150 volts and 100 milliamperes with reasonably good regulation, has its output circuit connected in series with that of a rectifier 11. A-C. voltage is applied to the anodes of the rectifier 9 through a center tapped transformer 10. The cathode of the rectifier 9 is connected through a filter circuit including a choke 13 and a capacitor 14 to the negative side of the output circuit of the rectifier 11. The rectifier 11 is energized from the portion of the ripple voltage on a filter choke 13 in the circuit of the rectifier 9, which excites a resonant circuit comprising inductance 15 tuned to the ripple frequency by a capacitor 17. A tap 19 on the choke 13 is adjusted so that the rectifier 11 will provide an output voltage of, for example, 450 volts at a load of 1 milliampere. A diode 21 is connected across the output circuit of the rectifier 11. The high impedance tuned circuit 15, 17 can only supply small currents. For high current demands, its voltage falls off and most of the load current flows directly from the low voltage circuit 9 over the diode 21.

Referring to Fig. 4, a similar circuit is shown including a resistor 23 in series with a high voltage rectifier 25 to limit the current obtainable at high voltage. A relatively high A-C. voltage is applied to the rectifier 25 from a secondary winding 24 of a transformer 26. A center tapped secondary winding 28 is provided on the transformer 26 and connected to the anodes of a full wave rectifier 29. The center tap of the winding 28 is connected to the negative output terminal of the rectifier 29. The output circuit of the rectifier 29 includes a filter choke 33 and a capacitor 35. The positive terminal of the out-

put circuit of the rectifier 29 is connected to the negative terminal of the output circuit of the rectifier 25 at a point 37. A diode 27 is connected across the output of the rectifier 25, and acts as an automatic switch which closes at the instant when the voltage across the output circuit of the rectifier 25 tends to go negative, thus preventing further voltage drop in the series resistor 23. For the wave forms shown in Fig. 1, the series resistor 23 may be given a value

$$\frac{E_2}{10 I_{(10)}}$$

where $I_{(10)}$ is the average current for 10 microsecond operation, at which the output voltage of E_2 of the rectifier 25 will decrease only 10 percent due to the resistor 23. The current in the resistor 23 is hence limited to $10 I_{(10)}$ for the 100 and 1000 microsecond operation, resulting in a power loss of only one tenth that obtained with a single supply of fixed voltage.

I claim as my invention:

1. A power supply system for sawtooth wave generators comprising a low voltage source of electrical energy, a high voltage source connected in series therewith, and a rectifier connected across said high voltage source.

2. A power supply system comprising a rectifier circuit, a filter including an inductor connected in the output circuit of said rectifier, a resonant circuit including a portion of said inductor, a second rectifier circuit having its input terminals connected across one of the reactance elements of said resonant circuit and its output circuit connected in series with the output circuit of said first rectifier, and a unidirectionally conductive device connected across the output terminals of said second rectifier circuit.

3. A power supply system for sawtooth deflection voltage generators for cathode ray tubes comprising a relatively low voltage source of electrical energy having low internal resistance, a relatively high voltage source of electrical energy having high internal resistance, a utilization circuit, connections whereby said sources are connected in additive series relation to said utilization circuit, and a unidirectionally conductive device connected across said high voltage source so as to prevent reversal of the polarity of the voltage between the output terminals of said high voltage source.
